(57) **CLAIM**

The ornamental design for a wearable video camera medallion with a circular display, as shown and described.

DESCRIPTION

FIG. 1 is a front view of a wearable video camera medallion with a circular display.

FIG. 2 is a back view of the wearable video camera medallion with a circular display of FIG. 1.

FIG. 3 is a right side view of the wearable video camera medallion with a circular display of FIG. 1.

FIG. 4 is a left side view of the wearable video camera medallion with a circular display of FIG. 1.

FIG. 5 is a bottom view of the wearable video camera medallion with a circular display of FIG. 1.

FIG. 6 is a top view of the wearable video camera medallion with a circular display of FIG. 1.

FIG. 7 is a front and right side perspective view of the wearable video camera medallion with a circular display of FIG. 1.

FIG. 8 is a back and left side perspective view of the wearable video camera medallion with a circular display of FIG. 1.

FIG. 9 is a front and left side perspective view of a wearable video camera medallion with a circular display of FIG. 1; and,

FIG. 10 is an exploded front and left side perspective view of the wearable video camera medallion with a circular display of FIG. 1.

The broken lines depict portions of the wearable video camera medallion with a circular display in which the design is embodied that form no part of the claimed design.
